UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 35,683, dated February 4, 1902.

Application filed June 3, 1901. Serial No. 63,044. Term of patent 7 years.

To all whom it may concern:

Be it known that I, OTIS A. MYGATT, residing at New York, in the county of New York and State of New York, have invented and 5 produced a certain new and useful Design for a Reflector for Artificial Lights, of which the following is a specification, reference being had therein to the accompanying drawings.

The design consists in the form or configuration and surface ornamentation for transparent reflectors for artificial lights.

Figure 1 is a side elevation of a reflector for artificial lights Fig. 2 is a broken section of same.

15 The body of the reflector A is in the approximate form of a segment of a hollow globe, but departs somewhat from true spherical form. The inner surface of the body is smooth. The outer surface is substantially 20 covered by pyramids C, arranged in rows, the bases of the pyramids being four-sided; but

owing to the form of the reflector the bases of these pyramids are not exactly square. The projection of the larger pyramids from the general surface is greater than that of 25 the smaller central pyramids.

The reflector is surmounted by a ring B.

The reflector is composed of transparent glass, which allows the ornamentation of the outer surface to show on the smooth inner 30 face.

What I claim, and desire to secure by Letters Patent, is—

The design for a reflector for artificial lights, as shown and described. 35

In testimony whereof I affix my signature in presence of two witnesses.

OTIS A. MYGATT.
